Application August 13, 1942, Serial No. 454,661

10 Claims. (Cl. 343—16)

1

This invention relates in general to a method of and apparatus for indicating on an oscilloscope a particular beam position of an antenna which assumes a plurality of different positions periodically.

In obstacle detection systems, sometimes known as radio locators, it is now proposed to cause a small deflection of a radio beam at regular intervals through the four quadrants of a circle which is perpendicularly located to the mean axis of the beam. This can be done either by wiggling the whole antenna system, or (for example, in the case of an antenna utilizing a parabolic reflector with a radiating element positioned slightly off-center, eccentrically, so to speak) by spinning the radiating element in a circle, or by spinning a deflecting element off the focus of the reflector. Such an antenna system, when employed for radio locating purposes, must not only be able to produce the beam deflections at regular intervals, but must be freely movable in all directions for scanning purposes and for pointing the antenna directly on the object to be detected.

The present invention provides, among other things, a simple and efficient method of indicating on an oscilloscope a mark characteristic of a particular beam position of the antenna system. The invention utilizes a minimum of auxiliary circuits, a minimum of control conductors, and successfully avoids the consequence of the random choice of synchronous position between the antenna beam deflecting device and the indicator prime mover.

The following is a detailed description of the invention accompanied by a drawing, wherein Fig. 1 illustrates the invention used in connection with a pulse type radio locating system, Fig. 2 is a circuit detail which can replace a mechanical switch shown in Fig. 1, Figures 3 and 4 are views showing for two different conditions the appearance of the image obtained on the screen of the cathode ray tube employed for indicating antenna beam position with respect to target in the horizontal plane, and Figures 5 and 6 are views showing for two different conditions the appearance of the image obtained on the screen of the cathode ray tube employed for indicating antenna beam position with respect to target in the vertical plane.

Before proceeding with a description of the invention, it is believed helpful to refer to the type of radio locating system which is shown employed in Fig. 1. The radio locating system is generally of the type described in my copending application Serial No. 441,311, filed May 1,

2

1942, now Patent No. 2,411,140 issued November 12, 1946, which employs a transmitter for transmitting periodically repeated radio wave pulses of extremely short duration. A receiver is used to receive the pulses which are reflected by the object to be detected. This system employs a directive antenna and other expedients at both transmitter and receiver by means of which the indications are confined to objects lying within a narrow range of angles. In order to produce the radio wave pulses, the oscillator of the transmitter is excited periodically through a spark gap switching device which is in series with the oscillator and the charging voltage source and to which is supplied at periodic intervals a voltage of sufficient value to break down the gap.

The transmitting antenna of the pulse type radio locating systems described above preferably comprises a parabolic antenna having, off-center, an eccentrically positioned radiating element which is rotated by a two-pole synchronous motor at about sixty times per second. The entire system is designed to radiate a pulse of ultra high frequency energy in each of the four quadrants of the circle traveled by the radiating element in each revolution. At a speed of rotation of sixty times per second, the pulses will be radiated 240 times per second, corresponding to a pulse for each quadrant position of each revolution of the antenna. The up and down beam firing positions of the radiating element determine the vertical position of the object to be detected, while the right and left beam firing positions of the radiating element determine the horizontal position. The radiation patterns or ears of the beam will, of course, be different for different quadrants of the circle as the radiating element rotates. The antenna system is so designed that the ears of the radiation patterns overlap in the up and down beam firing positions and also overlap in the right and left beam firing positions. Since the time interval between radiated pulses is quite long compared to the time of each pulse, it will be understood that a pulse reflected by a remote object to be detected will be received at the receiver located adjacent the transmitter during the same quadrant of rotation in which the original pulse is radiated.

If the pulses which are reflected from a remote object were originally radiated in the up and down positions of the rotating radiating element, these pulses will be received during the same up and down positions, and if these received pulses are of equal intensity, it follows that the horizontal plane of antenna system is pointed at the

object. If the reflected pulses received during the right and left positions of the rotating radiating element are also of equal intensity, it follows that the vertical plane of the antenna system is also pointed at the object. Under these conditions, the object to be detected is in a direct line with the focus of the antenna. If now, the parabolic reflector of the antenna is made of widely spaced wires in mesh formation, and the object is within visual distance, the illumination of a searchlight placed directly behind the reflector will illuminate the object.

If the received pulses reflected from the object are of unequal intensity, it is an indication that the antenna system is not pointed directly at the object, but to one side of the object.

The reflected pulses which are received are viewed on a pair of cathode ray oscilloscopes, one of which indicates the pulses received during the up and down positions of the rotating radiating element, and the other of which indicates the pulses received during the right and left positions of the rotating radiating element.

Inasmuch as a two pole synchronous motor is employed to rotate the antenna system, and since this motor can start either in the up or down position of the radiating element, it is important to provide a determination of whether the first reflected pulse received back from the object to be detected corresponds to either the up or the down position. The present invention furnishes a simple and efficient method of and apparatus for making this determination.

Referring to Fig. 1 in more detail, there is shown a pulse transmitter comprising an ultra high frequency oscillator M (here shown by way of example as a magnetron) capable of producing oscillations of about ten centimeters wavelength. This oscillator is periodically charged with a high polarizing potential through a spark gap T (air blast type) in circuit with a line TL. The end of line TL which is furthest removed from the spark gap T is connected through a rectifier L to the secondary winding of an induction coil P whose primary winding is connected to a main charging system comprising a source of direct current N and a switching device U. This part of the system serves to convert a relatively low voltage direct current charging potential from N to periodic high voltage pulses for charging line TL and corresponds to Figure 4 of my Patent 2,411,140. Reference is here made to my United States Patent 2,275,635, showing pulse charging circuits of interest in this connection.

A trigger spark system comprising an induction coil G, an auxiliary spark gap electrode associated with spark gap T, and a switching device F insures sparking at gap T only when line TL is fully charged and between charging pulses supplied to line TL by system U. That is, the trigger spark system insures the discharge of line TL across gap T and into the magnetron M between the times that the rectifier L is passing charging pulses to the line TL. The trigger spark switch device F is like the switching device U in that when one brush is connected to a segment on the commutator, the other brush of the same switching device is on an insulating segment or portion of the same commutator, and vice versa.

The directive antenna for radiating the extremely short pulses of ultra short wave carrier energy is indicated at A and comprises a rotatable radiating element positioned off the cen-

ter of a parabolic reflector. This radiating element is driven by a two-pole synchronous motor appropriately labeled, at a speed of 3,600 R. P. M., corresponding to sixty revolutions per second. The system is so designed that during each quadrant of the circle of each revolution of the radiating element, the magnetron will deliver a pulse to the antenna over connections X and Y, as a result of which there will be 240 pulses radiated per second. Each pulse may be of the order of one microsecond duration, or so.

Linked to the same shaft of the two-pole synchronous motor which drives the rotating radiating element, is a rotating arm 10 which makes contact with an arcuate metallic segment of switch SD for a time slightly greater than the duration of one quadrant. The arcuate shaped segment is of such length that arm 10 will engage it during the time the radiating element is, by way of example, in the up position and also in the right position at right angles to the first mentioned position. Associated with arm 10 is a bias battery 11 for supplying through the arcuate segment a bias to certain plates of the cathode ray oscilloscopes K₁ and K₂ for changing the origin of the cathode ray spot on the oscilloscopes. This will be described in more detail later.

The receiver 50 which receives the pulse reflected from the object to be detected, is connected to the radiating element of antenna system A through lead 12, concentric line resonator D, and line Z. Line Z is an odd multiple of a quarter wave long for energy of the carrier frequently generated by magnetron M.

Lead Y is coupled to the magnetron oscillator at C by means of a small loop, and is connected to the junction point B of leads Y and Z. This lead Z is an odd multiple of a quarter wave and is matched from an impedance standpoint to lead Y extending to the antenna, for pulses outgoing from the magnetron.

When short wave carrier pulses are sent out by the magnetron over lead X, the resonator D is energized through lead Z and this causes the spark gap E in the interior of the resonator to break down, thus producing a detuning action in D, as a result of which lead Z becomes a high impedance when looked at from point B. Thus, the main portion of the energy obtained from the magnetron M travels out to the antenna to be radiated thereby, and only a small portion of the energy derived from the oscillator passes over lead Z to maintain the spark across the gap E in resonator D.

As for energy received by the antenna A, the lead X is not matched at point C since it is closed at this point. Because the lead X has an electrical length equal to an odd multiple of a quarter wave length, the impedance of lead X at point B as seen from the antenna is high. However, energy received on the antenna will energize resonator D without producing sparking at E, as a result of which the radio frequency energy in resonator D will pass to the receiver 50 for subsequent utilization by the oscilloscopes K₁ and K₂. The reason why the incoming or received energy will not cause the spark gap E in the resonator to break down while the outgoing energy from the magnetron M will cause a breakdown of the gap E, is because the latter energy is far more intense than the former.

When the magnetron is caused to oscillate by virtue of the surge of current through the spark gap T, the current through the magnetron will

pass through a small resistor R or reactance as a result of which a pulse is initiated which is passed through pulse amplifier V_3 , whose output causes the saw tooth generator W to start. This saw tooth generator works on the first grids of vacuum tubes V_1 and V_2 , thus controlling the current through the tubes. The time constants of the saw tooth generator are adjusted for the maximum distance range to be observed, by making the time of sweep of the generator correspond to the particular distance to be checked. As an example, the particular maximum distance of the radio locating system to be observed may be twelve miles if the rotating antenna system is to be used in connection with a searchlight. On the other hand, the range of distances may be sixty miles, more or less, as desired, with the rotating antenna described above.

Vacuum tubes V_1 and V_2 are normally non-conducting on account of the cathode bias produced by resistors 13 and 14, respectively, and will pass current when the cathode bias is reduced. The reduction in cathode bias to render the tubes V_1 and V_2 conductive is obtained by means of switch S . The contact arm of switch S is connected to ground and rotates to cause engagement with segments N_1 to N_4 and O_1 to O_4 . Segments N_1 to N_4 , inclusive, are connected together and to a point on cathode bias resistor 14. Segments O_1 to O_4 , inclusive, are also connected together and to a point on cathode bias resistor 13. It should be noted that the segments labeled N_1 , N_2 , N_3 and N_4 alternate with the segments labeled O_1 , O_2 , O_3 and O_4 . The rotating switch or scope selector S may be driven by a synchronous motor having any number of poles. If, as shown in the drawing, a four-pole machine is chosen, the number of segments on the selector commutator will be eight. Alternate contacts or segments of the selector S are connected together, and each such group of four contacts controls the on and off condition for the saw-tooth sweep of each of the two cathode ray oscilloscopes K_1 and K_2 . Oscilloscope K_1 will give a horizontal sweep, while oscilloscope K_2 will give a vertical sweep in the particular arrangement illustrated.

When vacuum tubes V_1 or V_2 pass current, the voltage drop in resistors Q_1 or Q_2 , respectively, will control certain sweep or deflection plates of the oscilloscopes K_1 or K_2 , as shown.

Returning now to the operation of switch SD , the bias on arm 10 thereof, which is only effective in the up position and in the right position of the rotating radiating element, will cause the sweep starting points on the oscilloscopes to be slightly displaced relative to the sweep starting points when the radiating element is in the down position and in the left position.

In the operation of the system as a whole, let us assume that the switch SD is in the position shown in the drawing. The spark gap T will break down in the quadrant in which the switch SD is shown (gap T breaks down once in each quadrant in each revolution of the radiating element), as a result of which a pulse from the magnetron will pass out to the radiating element. This same pulse will produce a high impedance at point B looking toward the receiver 50, thus blocking the receiver solely for the duration of the outgoing pulse. At this same time, a portion of the pulse from the magnetron will pass through amplifier V_3 which will cause the start of the saw-tooth generator W . Tube V_2 will be conductive because of the decrease in its cath-

ode bias, assuming the rotating contact arm of switch S to be at this particular moment on one of the N segments. The output of the sawtooth generator through tube V_2 will now produce a vertical sweep of the cathode ray in oscilloscope K_2 . At a later moment when the rotating arm of switch S is on one of the O segments, the tube V_1 will become conductive to produce a horizontal sweep of the cathode ray in oscilloscope K_1 . It should be noted that the anode of tube V_2 is connected to the lower vertical deflection plate of oscilloscope K_2 , while the anode of tube V_1 is connected to the left horizontal deflection plate of oscilloscope K_1 . This vertical sweep is scaled according to the range of distances to be observed from the antenna to the object to be detected. A reflected wave (sometimes called an echo) returned from the object to be detected will pass through the receiver 50 and cause a horizontal deflection on oscilloscope K_2 by means of the right hand deflection plate of K_2 in circuit with the video output of the receiver. (It should be understood that the receiver is now in condition to receive because the outgoing pulse which blocks the receiver is extremely short compared to the time interval between successive outgoing pulses.) This horizontal deflection will be some distance down on the vertical sweep of K_2 , depending on the time for the original transmitted pulse to be returned as an echo or reflected pulse to the antenna. The extent of horizontal deviation of the sweep is a measure of the intensity of the returned (reflected) pulse. The vertical sweep in scope K_2 will continue during the horizontal deflection produced by the returned pulse and gives width to the observed pulse.

The bias on arm 10 of switch SD is connected across the grounding resistor R_1 , by virtue of connection 15. Thus, resistor R_1 is in circuit with one vertical plate of oscilloscope K_2 and one horizontal plate of oscilloscope K_1 . This bias changes the location of the origin of the ray spot (sweep starting point) on the oscilloscope, so that the operator, knowing the direction of displacement produced by SD , can determine when the antenna radiating element is in the particular up position corresponding to the quadrant at which the bias is effective. Horizontally observed deflections on the vertical sweep oscilloscope K_2 caused by reflected pulses received during the time the antenna is in the up position will thus be displaced vertically from the deflections on the same oscilloscope K_2 caused by the reflected pulses received during the time the antenna is in the down position.

Inasmuch as the arcuate segment of switch SD is slightly longer than 90° , it is effective for the up vertical position of the antenna and also for the right horizontal position of the antenna. Consequently, echo or reflected pulses passed on by the receiver 50 to the oscilloscope K_1 while the antenna is in the right and left horizontal positions will produce vertical deflections on the horizontal sweep of the oscilloscope K_1 , but the bias on arm 10 of switch SD will change the location of the origin of the ray spot (sweep starting point) in K_1 , so that the operator can determine when the antenna is in the particular right horizontal position.

The horizontal deflections on the vertical sweep oscilloscope K_2 due to received pulses passed on during the up and down positions of the antenna will appear one above the other, and similarly, the vertical deflections on the horizontal sweep oscilloscope K_1 due to received pulses passed on

during the right and left positions of the antenna will appear adjacent each other. Due to the speed of rotation of the antenna through its four quadrants and the rapidity of the radiated pulses, the deflections appearing on the oscilloscopes will appear stationary on account of the persistence of vision.

Figures 3 to 6 show the appearance of the horizontal and vertical deflections or pips on the screens of the tubes K_2 and K_1 , respectively, for different positions of the antenna beam center axis with respect to the target as indicated by the legends.

An advantage of the present invention lies in the fact that the operator can always determine immediately which deflections on the oscilloscopes correspond to the different positions of the spinning antenna, despite the fact that the synchronous two-pole motor driving the antenna can lock in synchronism at either of two positions displaced 180° with respect to each other.

Fig. 2 illustrates a quarter phase network system which can replace the oscilloscope selector switch S . This system includes a network 20 having two branches arranged in electrically parallel relation and connected between ground and a source of sixty cycle supply. One branch includes a condenser 21 and two resistors R_2 , R_3 in series, while the other branch includes an inductance coil 22 and a resistor R_4 in series. A pair of connections 23 and 24 extend from suitable points on the network branches to the primary windings of audio transformers 25 and 26 , respectively, whose secondary windings are connected to rectifiers 27 , 28 and 29 , 30 for producing pulses which can be applied to the second grids of the tetrode vacuum tubes V_1 and V_2 of Fig. 1. Due to the fact that the voltages in the two branches are 90° out of phase relative to each other, the pulses from the rectifiers will supply pulses alternately to the grids of the vacuum tubes V_1 and V_2 to render these tubes alternately conductive.

What is claimed is:

1. A directive antenna system comprising a parabolic reflector and a radiating element positioned off-center in front of said reflector, a motor driving said element in a circle about the axis of said reflector, a pair of cathode ray tubes one for indicating the vertical positions of said radiating element, and the other for indicating the horizontal positions of said radiating element, translating apparatus coupled between said radiating element and said cathode ray tubes, and circuit means coupled to said cathode ray tubes and supplying a bias to said tubes in only one vertical position and in only one horizontal position of said radiating element for producing indications characteristic of these positions of said radiating element.

2. An obstacle detection system comprising a transmitter for periodically sending short wave carrier pulses of short duration spaced in time an amount which is large compared to the time of each pulse, a directive antenna system for said transmitter including a parabolic reflector having a radiating element positioned off-center, a two-pole synchronous motor for rotating said radiating element in a circular path, whereby said antenna system periodically assumes a plurality of beam positions, an electronic tube system, and means coupled to said rotating radiating element for applying to said electronic tube system potentials during only such times when said radiating element is in certain positions.

3. A directive antenna having a two-pole syn-

chronous driving motor for causing said antenna to assume sequentially four different beam firing positions corresponding to the four quadrants of a circle, first and second cathode ray tubes each having electron ray deflection elements, translating apparatus coupled between said directive antenna and said cathode ray tubes, an arcuate shaped segment overlapping two adjacent quadrants of the circular path travelled by said antenna and adapted to be energized during the time said antenna is passing through said two quadrants, and a circuit connection from said segment to different electron ray deflection elements of said cathode tubes, whereby said tubes provide indications characteristic of the positions of said antenna in all four quadrants.

4. An antenna adapted to sequentially assume different beam positions, a motor linked to said antenna through a drive shaft, means driven by said drive shaft and arranged to close an electrical circuit during only a relatively small arc of the circle traversed by said shaft while it is rotating, a cathode ray oscilloscope having electron ray deflecting elements, a sweep circuit connected to certain of said deflecting elements, said electrical circuit including means for applying a potential of predetermined duration to another of said deflecting elements of said cathode ray oscilloscope, whereby the particular beam position of said antenna corresponding to the position of said small arc is identifiable.

5. An object detection system including a directive antenna comprising a reflector and a radiating element eccentrically positioned in front of said reflector, a motor having a shaft linked to said element for rotating the same, and means for transmitting a single pulse of ultra short wave energy to said element for each quadrant of the circle through which said element is rotated, said pulses being uniformly spaced and being short compared to the time intervals between them, a receiver coupled to said antenna, and means in said system for distinguishing between the pulses received during the different quadrants.

6. An object detection system including a directive antenna, a motor for effectively causing the antenna to assume different positions of effectiveness in a circular path, means for transmitting a single pulse of high frequency energy from said antenna during each quadrant of said circular path, said pulses being uniformly spaced and being short compared to the time intervals between them, a receiver coupled to said antenna, and means in said system for distinguishing between the pulses received during the different quadrants.

7. For use with a radio locating system which transmits a single pulse from a rotating antenna structure during each of the left-right and up-down quadrants of the circle through which said antenna structure passes and which utilizes the reflected pulses from an object to be detected, an electronic indicating arrangement for distinguishing between the reflected pulses received by said locating system during the antenna rotation in said different quadrants, said arrangement comprising a pair of cathode ray tubes at said locating system, means for applying received pulses to one of said tubes during only the motion of said antenna structure through said left-right quadrant and to the other of said tubes during only the motion of said antenna structure through said up-down quadrants, means for sweeping each of the cathode rays of said tubes

along a time axis in synchronism with said pulse transmission, and means responsive to said antenna rotation for displacing the cathode ray sweep of said one tube during the antenna rotation through one of the left-right quadrants and for displacing the cathode ray sweep of the other tube during the antenna rotation through one of the up-down quadrants.

8. An obstacle detection system comprising a transmitter for periodically sending short wave carrier pulses of short duration spaced in time an amount which is large compared to the time of each pulse, a directive antenna system for said transmitter including a parabolic reflector having a radiating element positioned off-center, a two-pole synchronous motor for rotating said radiating element in a circular path, whereby the pattern of said antenna system periodically assumes a plurality of beam positions, an electronic tube indicating system, and electronic means coupled to said rotating radiating element for applying to said electronic tube system potentials during only such times when said radiating element is in certain positions.

9. A directive antenna having a synchronous driving motor for causing said antenna to sequentially assume different positions of effectiveness, a transmitting system for applying pulses to said antenna to be radiated thereby during said different positions, a cathode ray circuit, an electronic means having an input circuit responsive to the motion of said driving motor solely during certain positions thereof and an output circuit coupled to said cathode ray circuit, whereby said cathode ray circuit indicates by characteristic markings the different beam firing positions of said antenna.

10. In an obstacle detection system employing an antenna which assumes a plurality of beam positions periodically, and a transmitter and a receiver coupled to said antenna, the method of operation which includes generating pulses which are short compared to the time interval between them, radiating a pulse from said an-

tenna during each of said beam positions, receiving on said antenna reflected pulses returned from a remote obstacle upon which said radiated pulses impinge, producing electronic indications of said received reflected pulses by means of a stream of charged particles, electronically producing a pulse during selected ones of said beam positions, and deflecting said stream of charged particles by said pulse only during said selected 10 firing positions.
